[57] CLAIM

The ornamental design for a conductive ink traces pattern on a medium, as shown and described.

DESCRIPTION

FIG. 1 is a front perspective view of a conductive ink traces pattern on a medium, showing my new design therefor, where the medium is of fabric, plastic, Mylar, metal, rubber, or wood and is shown in dotted lines;

FIG. 2 is a frontal view therefor;

FIG. 3 is a rear view therefor (where the medium is transparent);

FIG. 4 is a side view therefor, showing the left side;

FIG. 5 is a side view therefor, showing the right side;

FIG. 6 is a top plan view therefor; and,

FIG. 7 is a bottom plan view therefor.

The broken line showing throughout the drawing views is included for the purpose of illustrating environmental structure only and forms no part of the claimed design.
